APPARATUS FOR HEATING OR IGNITING
WELL FORMATIONS

Karol L. Hujšak, Tulsa, Okla., assignor to Pan American Petroleum Corporation, Tulsa, Okla., a corporation of Delaware
Original application Apr. 8, 1963, Ser. No. 271,262, now Patent No. 3,223,165, dated Dec. 14, 1965. Divided and this application Apr. 28, 1965, Ser. No. 458,511
4 Claims. (Cl. 158—28)

This application is a division of my copending application, Serial No. 271,262, filed April 8, 1963, now Patent 3,223,165, granted December 14, 1965.

The present invention relates to a method and apparatus suitable for heating or effecting ignition of a hydrocarbon-containing formation penetrated by a well. More particularly, it is concerned with a novel heater design and method for use thereof involving application of pyrophoric material to ignite a fuel-oxygen containing gas mixture the composition of which is controlled so as to regulate the resulting flame temperature. The expression "flame temperature," as used herein, is intended to refer to the final adiabatic mixture temperature of the oxidation or combustion products and excess air.

Many methods have been employed in the prior art for applying heat to hydrocarbon-containing formations such as, for example, by electrical means, by injecting heat transfer agents such as steam, hot oil, etc., into the well and by burning natural gas in the well bore. One of the principal difficulties has been that in the course of heating the formation to ignition temperature, the casing or screen as well as any other equipment in the vicinity of the heated zone is damaged by the excessive temperatures generated. In fact, the temperatures produced have been so high that the burner itself was considered an expendable item. The electric heaters employed for ignition and for paraffin deposition control have been subjected to a number of practical problems, including shorting out; in some instances, such equipment has been lost in the hole and is extremely difficult to recover.

Accordingly, it is an object of my invention to provide a safe and efficient means to ignite or heat a hydrocarbon-bearing zone at a temperature that will not damage the casing. It is another object of my invention to provide a means for readily igniting the heater in the event the flame is extinguished owing to fluctuations or surges in the fuel-air system. It is a further object of my invention to provide a means for stimulating the flow of oil from an underground deposit thereof by the use of heat without the formation of coke on the heat source, or elsewhere, in objectionable amounts. It is still another object of my invention to provide an apparatus suitable for heating an oil-bearing or similar sand to temperatures of the level required for initiation of underground combustion operations.

Briefly, my invention comprises a wire line retrievable igniter or heater adapted to operate on gaseous or vaporized fuels. Such fuel is preferably passed down the tubing and air down the annulus. When all the air in the tubing has been displaced with fuel, a lubricator having a side opening is purged with an inert gas, such as nitrogen, and a pyrophoric material added to the cup portion of an igniter tube in the lubricator. The cup may contain crushed charcoal, or the equivalent, to prevent the pyrophoric material—if it is a liquid—from splashing and spilling over. The charcoal acts as a secondary ignition source if gas flow is temporarily interrupted due to pressure surges or other causes. Thereafter, the igniter is lowered to a level 15 to 20 feet from the bottom of the tubing. Gas flow is then stopped for a short time and

2

air flow down the annulus is continued in order to purge the well bore below the bottom of the tubing free from a combustible fuel-air mixture. The igniter is then lowered further until it seats in the bottom of the tubing. At the same time, flow of fuel down the tubing is resumed. As soon as the pyrophoric material in the igniter is contacted with air, it ignites and, in turn, ignites the fuel. The igniter is then withdrawn from the burning zone and burning continues in the main burner structure provided at the bottom of the tubing. The burner can operate on a mixture of air and a light hydrocarbon, preferably natural gas. The fuel and air are separately pumped to the burner through the tubing and casing, respectively. They mix at the end of the tubing inside a heat shield. A large excess of air, e.g., up to 500 percent of stoichiometric, is used to keep the adiabatic mixture temperature within the desired range. Satisfactory operation of my invention has been observed as low as 500° F. adiabatic mixture temperature; however, I generally prefer to operate within a temperature range of from about 900° to about 1,100° F.

The expression "inert gas," as used herein, refers to any gas or vapor that does not react with the pyrophoric material used. Carbon dioxide, while normally considered an inert gas with respect to some pyrophoric substances, cannot be used for this purpose in my invention where triethylborane, for example, is employed because carbon dioxide readily reacts with it.

In the accompanying drawings,
FIGURE 1 is a vertical view, partly in section, of the apparatus of my invention being installed in an oil well;
FIGURE 2 is a detailed sectional view of the heater of my invention showing the igniter tube;
FIGURE 3 shows a cross-section of the apparatus and associated equipment used to prevent fluids from entering the tube when the latter is lowered into the well containing fluids and prior to placing the igniter tube in operating position;

FIGURE 4 is a sectional view of a modification of the igniter tube shown in FIGURE 2.

Referring now to FIGURE 1, a well 2 having protective casing 4 is equipped with a lubricator 6 affixed to a wellhead 8. Igniter tube 10 is lowered on cable or wire line 12 into lubricator 6 while valve 14 is closed. The igniter tube comes to rest in the lubricator at a level such that the lower cup portion of the igniter is opposite T plug 16. A valved line 18 enters lubricator 6 a short distance above plug 16 and is used as a conduit through which inert purge gas is introduced into the lubricator. Tubing string 20 secured at the top by wellhead 8 carries heat shield 22 held on the lower end of said string by means of threaded coupling 24. In addition to flow line 26, the well is equipped with valved fuel line 28 which flows into tubing 20, combustion air line 30 opening into the well annulus, and a second air line 32, off of line 30, fitted with valve 29 and check valve 31 and communicating directly with tubing 20.

In FIGURE 2, igniter 10, resting in seating nipple 34, comprises a barrel section 11 having a lower cup portion 36 suspended from barrel 11 by means of metal bars 38. A relatively fluid-tight seal above and below the seating position is provided by O-ring 40 fitted into the groove in shoulders 42 of the igniter barrel. Seating nipple 34 is held in position by means of spacer bars 44, the opposite ends of which are anchored to heat shield 22 having an inner refractory cement lining 46. The upper end of igniter 10 is engaged to a sinker bar 48 by means of threaded coupling 50. The upper portion of sinker bar 48 is threadededly engaged to cable clamp assembly 52 which, in turn, is connected to cable head 54. Also near the upper end of sinker bar 48 are gas ports 49

through which fuel flows when igniter 10 is seated in nipple 34. Resting inside igniter 10 is well 56 containing a thermocouple 58, e.g., a chromel alumel thermocouple. This thermocouple has lead wires 60 and 62, the former of which is grounded to the sinker bar at 64 while the latter 62 runs on up through hollow cable 12 to a temperature recorder (not shown).

Referring to FIGURE 3, there is shown a plug 66 resting in the lower portion of nipple 34. The plug which may be composed of a laminated plastic or a soft metal, such as aluminum, is held by friction in nipple 34 through the use of O-ring 68 and is prevented from moving further into nipple 34 by means of shoulder 67. Plug 66 serves to prevent entry of fluids into the tubing when the burner assembly, i.e., heat shield 22 and seating nipple 34, is lowered into the well. The burner assembly, with the tubing plug installed, is attached to the lowermost joint of tubing 20 and should be landed so that the bottom of heat shield 22 is about 2 feet or so above the highest level of perforations 78 or open hole.

The burner assembly confines the flame and protects the casing from excessive temperatures. Assemblies constructed of Inconel, type 316 and type 304 stainless steel have been used with success. The diameter of heat shield 22 should be as large as practical for the size casing in the well at the level the heater is to be used. Also, it is important that the openings between supports 44 be as large as possible to permit the flame temperature inside shield 22 to be maintained as low as possible.

FIGURE 4 is a modification of the igniter shown in FIGURE 2 having a restricted extension 70 of barrel 11 resting in cup 71. Extension 70, which is welded to the bottom of cup 71, has perforations 72, permitting fuel to contact pyrophoric material 74 and force the latter into the well where it spontaneously ignites on contact with oxygen. The igniter design shown here is useful to prevent inactivation of the pyrophoric material as a result of hydrocarbon absorption. Such inactivation has been observed to occur where the pyrophoric substance is a liquid, such as triethylborane. There is a strong tendency for C_3 and heavier hydrocarbons to absorb into the triethylborane or similar materials and, if the latter becomes diluted with hydrocarbons to the extent of about 80 percent, the resulting mixture does not spontaneously ignite in the presence of air. Under these circumstances, precaution should be taken to prevent such hydrocarbon absorption by placing in the annulus between extension 70 and cup 71 a temporary sealant 76 such as, for example, a heavy chassis grease, while the igniter is still in the lubricator. Absorption of hydrocarbons inside igniter 10 by the pyrophoric material is prevented by placing a blanket of inert gas next to said material. This is done by pressuring up lubricator 6 with nitrogen or other suitable inert gas to tubing pressure after which it is closed and valve 14 opened. Ignition can then proceed in a normal manner. Under these conditions, the triethylborane, or other pyrophoric material, is in contact with an inert gas blanket which usually extends the full length of barrel 11. Generally, I prefer to pressure up lubricator 6 to a level approximately half that existing in tubing 20. This is for the reason that if the volume occupied by the inert gas is relatively large, there is a possibility that in forcing the triethylborane out of cup 71 with a gaseous fuel via tubing 20, the triethylborane will ignite and burn before it is able to contact the fuel. Once the heater reaches the level in the well where ignition is to occur, gas is pumped down tubing 20, ports 49, through barrel 11 and extension 70, forcing pyrophoric material 74 and sealant 76 out of the aforesaid annulus and into the well to ignite the combustible mixture therein.

In operation, heat shield 22 and seating nipple 34, which constitute the burner assembly, together with tubing plug 66, are lowered down the well on tubing string 20 to a level approximately 2 feet above the top row of perforations 78 or open hole, whichever the case may be. After well-

head 8 has been assembled and the necessary surface installations completed, it is preferable to run a sinker bar on cable 12 through the lubricator to tubing plug 66 in order to locate the seating nipple accurately. With both tubing and casing open to air flow via lines 30 and 32, displacement of well fluids is begun. When the liquid level reaches top perforations 78, casing or annulus pressure drops. Check valve 31 prevents equalization of pressure via lines 30 and 32, resulting in a differential being created between tubing string 20 and the annulus. This pressure differential generally is great enough to force plug 66 out of the lower end of nipple 34 and into the well. When pressures equalize, a sinker bar should again be run through seating nipple 34 to confirm the removal of plug 66.

When plug 66 is removed, gas flow via line 28 is started down tubing 20. Valve 29 is closed and air flow is commenced down the annulus via line 30. From the gas injection rate and tubing capacity, the time to completely displace the air from the tubing can be determined. It is usually desirable to inject two tubing volumes of gas (noncombustion supporting gas) to insure complete purging of the air.

Igniter 10 should be installed in lubricator 6, after filling cup 36 with 4 to 8 mesh charcoal and then located at the level shown in FIGURE 1. Lubricator 6 is next purged free of air with cylinder nitrogen by pressuring to about 50 p.s.i.g. through line 18 and then depressuring. When the purging step is completed, plug 16 is removed and the igniter cup, containing ground charcoal, is filled to the top with triethylborane. This can be done conveniently through the use of a one-foot length of $\frac{1}{8}$ " copper tubing attached to a cylinder of triethylborane. After the igniter cup is full of triethylborane, T plug 16 is replaced and tightened in the lubricator T. The entire operation of filling cup 36 with triethylborane should be done quickly and with minimum opportunity to introduce air into lubricator 6. Tubing valve 14 below lubricator 6 should be opened as soon as the purging step is completed. Igniter tube 10 is then lowered to within about 20 or 25 feet of seating nipple 34. At this time, gas flow is stopped while air flow is continued via line 30 and the well annulus in order to purge the well below heat shield 22 free of the gas-air mixture. In this manner air and combustible gas are driven into formation 39 via perforations 78 so that only air remains below the burner assembly. Igniter tube 10 is then lowered to seating nipple 34 and gas flow is started down tubing 20 at the previously determined rate into igniter 10 via ports 49. Successful ignition is generally evidenced by an immediate drop in air rate and a rise in injection pressure. The rate of pressure rise may be high enough to stop the flow of gas out of the end of tubing 20, causing the flame to go out. The maximum tolerable rate of pressure rise should be calculated in advance and the actual rate of pressure rise held to not over about $\frac{1}{2}$ that value by reducing air flow at a suitable bleed valve (not shown) upstream in air line 30. Using a well depth of 1,000 feet, the well being equipped with 7" casing and 2" tubing, such calculation is made as follows:

Assume a gas injection rate of 400 s.c.f.h. and an air injection rate of 20,000 s.c.f.h., at 500 p.s.i.g. pressure. The tubing volume is 25.4 cu. ft. The maximum rate at which tubing pressure can be increased is:

$$\frac{14.7 \times 400}{60 \times 25.4} = 3.85 \text{ p.s.i. per minute}$$

The casing volume (annulus between casing and tubing) is 237 cu. ft. The maximum rate at which casing pressure can increase is:

$$\frac{14.7 \times 20,000}{60 \times 237} = 20.7 \text{ p.s.i. per minute}$$

In order to prevent stopping the gas flow out of the end of tubing 20 and pressuring the latter with air from the

annulus, the rate of pressure increase at wellhead 8 should be kept below 3.85 p.s.i. per minute in this example. Preferably, the maximum rate of pressure increase would be held at about one-half this value by reducing the air injection rate by opening an air bleed valve upstream of the air meter (not shown). As soon as pressures stabilize, the air rate should be returned to normal slowly.

Thermocouple 58 should provide additional evidence of burner operation. Temperatures in the order of about 700° F. or higher are generally indicated. After about 15 minutes with igniter tube 10 in seating nipple 34, the tube should be pulled off the seat and up the well about 20 feet. This prevents sticking on the seat and insures the possibility of removal for reignition in case it is necessary as a result of a flow interruption. Igniter tube 10 may be lowered to seating nipple 34 periodically to test temperatures. If desired, the Inconel end of igniter tube 10 may be filed or polished to brightness before running to seating nipple 34. The polished area will be straw-colored or blue after short exposure to heat.

After the desired amount of heat has been injected, tubing string 20 should be purged free of natural gas. This operation is conveniently carried out by introducing about two 220 s.c.f. cylinders of nitrogen into the suction gas compressor, followed by opening the suction to air. The time required for the nitrogen to reach the burner should be computed. The burner can generally be observed to go out as the result of smooth action of the air rate and pressure pens on the air meter at approximately the calculated time.

Refractory cement 46 may be chosen from a wide range of materials such as the high alumina cements which generally contain from 35 to 40 percent Al_2O_3 , 30 to 35 percent CaO , 10 to 15 percent Fe_2O_3 , and a combined percentage of silicon and magnesium oxides of from 5 to 10 percent. Any castable refractory material capable of withstanding temperatures of at least about 3,000° F. is suitable. One particular refractory I have found useful for this purpose is Alfrax refractory cement manufactured by the Carborundum Company, Perth Amboy, New Jersey. This is a castable material which can be applied as a mud after mixing with water. The refractory sets within about 24 hours and generally firing before use is unnecessary.

Substantially any pyrophoric material, liquid or solid, is satisfactory for my purpose. Thus, in addition to alkyl boranes, typified by triethylborane, there may be mentioned pyrophoric metals, phosphorous, aluminum borohydride, aluminum alkyls, pentaborane, and the like.

The igniter and burner assembly of the design described herein have been used successfully over a wide

range of conditions, i.e., pressures ranging from 250 to 900 p.s.i.g., depths up to about 3,300 feet, and heat output rates of 7 to 10 million B.t.u. per day, based on the natural gas consumed. The maximum amount of heat generated in any single application of this heater was 67 million B.t.u. in a seven-day period. Ordinarily, a heat generation rate in excess of about 10 million B.t.u. per day is not desirable because local overheating of the casing near the burner level can occur.

10 I claim:

1. A burner apparatus comprising an elongated housing open at both ends, a first hollow open ended member extending part way into one end of said housing, spaced members about said one end holding said first hollow member in alignment with the longitudinal axis of said housing and in substantially concentric relationship with said housing, a second hollow open ended member detachably mounted in and surrounded by said first member, and an open container in said housing affixed to the end 15 of said second hollow member.
2. In a burner apparatus the combination comprising an elongated open ended housing, a hollow open ended member extending part way into one end of said housing, spaced members about said one end holding said hollow member in alignment with the longitudinal axis of said housing and in substantially concentric relationship with said housing, and a plug within said hollow member adapted to be displaced out of said member into said housing by means of a pressure differential.
3. The burner apparatus of claim 1 in which said container surrounds one end of said second member, said one end of said second member being affixed to the bottom of said container, and at least one opening near said one end of said second member thereby establishing communication between said container and said second member, said container being of sufficient diameter to define an annular space between said one end and said container.
4. The burner apparatus of claim 1 in which said container is suspended by means of spaced supports to the end of said second member in said housing.
